CUTHBERT E. REEVES, OF BUFFALO, NEW YORK

INTERLOCKING SWITCH

Application filed February 14, 1930. Serial No. 428,347.

This invention relates to a starting switch for motor vehicles and has particular reference to that type disclosed in my copending application filed October 18, 1929, Serial No. 400,637. In this copending application I disclosed and set forth an interlocking switch for preventing the operation of the self starter while the engine was in motion, which interlock was effected through an electric circuit.

The present invention has for its primary aim to provide a mechanical interlock to thwart or frustrate any attempt to close the starter circuit while the engine is in motion, or without first breaking the ignition circuit before again closing the starter circuit. The invention further resides in means for compelling the movement of the ignition switch to an "off" position after a starting operation has once been effected and preliminary to effecting a subsequent starting operation.

In the drawing:

Fig. 1 is a diagrammatic sectional view illustrating the improved switch mechanism in its "off" position.

Fig. 2 is a transverse section therethrough immediately behind the front wall of the casing, further disclosing the relation of parts in their "off" position.

Fig. 3 is a fragmentary view similar to Fig. 1 but depicting the parts as the switch control is being moved past the running position as occasioned by a starting operation.

Fig. 4 is a view similar to Fig. 3 illustrating the parts in their starting position.

Referring more in detail to the accompanying drawing, the numeral 1 designates a switch control which in the present showing is in the form of a lever fulcrumed at 2 and having a work arm 3 provided with a cam surface 4 for camming against the movable switch element 5 of the ignition switch 6 from which the ignition circuit wires 7 lead. The control 1 is also designed for closing a starter circuit switch herein depicted as comprising a fixed contact 8 and a movable contact 9 which latter is coupled to the work arm 3 by a link 10, the circuit wires 11 of the starter circuit being properly connected to the respective contacts 8 and 9. The dif-

ferent circuit wires may comprise the main circuit wires properly armored or protected, or they may comprise relay or auxiliary circuits leading to automatic circuit closers elsewhere located on the motor vehicle. A spring 12 may be provided for returning the control 1 from a starting position, indicated in Fig. 4, to the "on" or running position indicated in Fig. 3.

A lock 13 is arranged and mounted for movement into a position for obstructing movement of the control from the on or running position back to the starting position to frustrate any attempt to again close the starter circuit after the engine has once been set in motion. This lock or latch is conveniently mounted on a resilient support 14 which normally urges the latch over into the path of the control 1.

Means are provided for preventing functioning of the latch upon movement of the control from off position to the starting position, which means in the present showing is of a mechanical nature and comprises a keeper plate 15 movably mounted for movement from an operative to an inoperative position and vice versa, the mounting herein shown being a pivotal one and consisting preferably of the fulcrum 2 so that the keeper plate and the control have a coaxial mounting. The plate 15 has a keeper part 16 designed for riding down on the beveled face of the latch 13 to cam or shift the same laterally from the path of movement of the control 1. When this keeper part 16 is moved out of engagement with the latch 13 the latter is free to return to a control obstructing position indicated by the dotted showing 13' in Fig. 2. As a means for moving the keeper plate to its operative position when the control is moved to an off position there is provided a play connection between the keeper plate and the control which is herein depicted as consisting of a stop shoulder 17 carried by the keeper plate 15 and extending into the path of the control lever. There is also provided a stop shoulder 18 on the plate 15 for extending into the path of the control lever at the opposite side thereof so that when the control is moved from its off position to its starting position 100

the keeper part 16 will be moved from engagement with the latch 13, as indicated in the dotted showing 16' in Fig. 3 and by the full line showing in Fig. 4. Such movement 5 brings the stop shoulder 17 into a position for being engaged by the control should the latter be returned to an off position from its on or running position thereby insuring an operative movement of the keeper part 16 to shift 10 the latch from its operative position.

In practice the switch mechanism may be arranged in any suitable position on the motor vehicle such as in a housing 19 disposed at the rear of the instrument board or panel 20 the latter serving as the front wall of the housing or switch box if desired and provided with a slot 21 through which the control 1 projects to a position readily accessible to the motorist. With the parts arranged in their relative positions depicted in Fig. 1 the control is lifted through the on or running position indicated in Fig. 3 to the starting position of Fig. 4. At the start of this movement the latch 13 is withheld from its operative position by the keeper part 16 and is released as the control is moved beyond the running position to the starting position by reason of the engagement of said control with the stop shoulder 18. The starter circuit being closed the motor vehicle engine is set in operation and the control returned to the on position indicated in Fig. 3 either manually or by other means, such as the spring 12. When returned to the running position the control 35 cams against the latch 13 and moves thereby whereupon said latch returns to an overhanging position for obstructing a return movement of the control to the starting position. The control is therefore confined between the 40 movement obstructing latch 13 and the stop shoulder 17. Return movement to a starting position is therefore prevented while movement to the off position is permitted.

The motorist is therefore compelled to re-
45 turn the control to a full off position before
again attempting to bring into operation the
starter, and as the control is moved to the
off position the cooperation of the stop shoul-
der 17 with the control brings the keeper 16
50 down against the latch 13 to shift it from the
control obstructing position whereupon the
control is free to move again to the starting
position.

What is claimed is:

55 1. Control means for an internal combustion engine having an ignition circuit and a starter mechanism, comprising a switch for said circuit and a switch for said mechanism, and means enforcing opening of the ignition circuit after once the engine has been started and preliminary to again closing the starting switch.

60

2. Control means for an internal combustion engine having an ignition circuit and a starting motor circuit, comprising a control

common to both circuits, and means for preventing movement of the control to a starting position after the engine has once been started and without first rendering the ignition circuit inoperative.

3. A combined starting and ignition control for motor vehicles comprising an ignition switch and a starter switch, a control movable from an off position first to a position for closing the ignition switch and then to a second position for closing the starter switch, said control being returned to the first position from the second position, and means operable by the control member for preventing return movement of the latter to the second position preliminary to returning said control to its off position.

4. A combined starting and ignition control for motor vehicles comprising an ignition switch and a starter switch, a control movable from an off position first to a position for closing both switches and then to a second position for opening the starter switch only, a latch for preventing return movement of the control member from its second position to its first position, and means for rendering said latch inoperative for permitting such control movement from an off position.

5. Control means for an internal combustion engine having an ignition circuit and a starting circuit, comprising a control movable from an off position through a running position in which the ignition circuit is closed to a starting position in which the both circuits are closed, a latch movable to an operative position for obstructing movement of the control from the running to the starting position, a keeper having play connection with the control and positionable thereby during movement of the latter from the starting to the running position to render the latch operative. 95 100 105

6. An interlock switch for motor vehicles comprising a pivotally mounted control lever movable from an off position through a running position to a starting position and vice versa, an ignition switch closed by and during movement of the lever from off position to its running position, a starting switch closed by and during movement of the lever from the running position to the starting position, means normally disposed in a position for obstructing movement of the lever from running position to the starting position, a keeper acting in its operative position to hold said means inoperative, and means connecting the lever to the keeper for rendering the latter inoperative by and during movement of the lever from its running position to its starting position whereby upon return of the lever to its running position said first means will function to prevent return movement of the lever to its starting position. 110

115

120

125

130

7. An interlock switch for motor vehicles comprising a pivotally mounted control lever movable from an off position through a running position to a starting position and vice versa, an ignition switch closed by and during movement of the lever from off position to its running position, a starting switch closed by and during movement of the lever from the running position to the starting position, means normally disposed in a position for obstructing movement of the lever from running position to the starting position, a keeper acting in its operative position to hold said means inoperative, and means connecting the lever to the keeper for rendering the latter inoperative by and during movement of the lever from its running position to its starting position whereby upon return of the lever to its running position said means will function to prevent return movement of the lever to its starting position, and means for returning the keeper to its operative position by and during movement of the lever from its running position to its off position.

8. An interlock switch for motor vehicles comprising a pivotally mounted control lever movable from an off position through a running position to a starting position and vice versa, an ignition switch closed by and during movement of the lever from off position to its running position, a starting switch closed by and during movement of the lever from the running position to the starting position, means normally disposed in a position for obstructing movement of the lever from running position to the starting position, and a keeper normally acting in its operative position and when the lever is in its off position to hold said means inoperative.

9. An interlock switch for motor vehicles comprising a pivotally mounted control lever movable from an off position through a running position to a starting position and vice versa, an ignition switch closed by and during movement of the lever from off position to its running position, a starting switch closed by and during movement of the lever from the running position to the starting position, a latch, means urging the latch to a lever obstructing position for obstructing movement of the lever from the running position to the starting position, a keeper plate pivoted coaxially with the lever and having a part for camming against the latch to move and hold it inoperative, and spaced stop parts on the plate at opposite sides of the lever for alternate engagement thereby for moving the keeper to an inoperative position upon initial movement of the lever from a running to a starting position, said shoulders being spaced sufficiently to permit return movement of the lever to a running position independently of the plate but insuring

movement of the keeper to its operative position upon movement of the lever from its running to its off position.

10. A starting and ignition control for an internal combustion engine, comprising an ignition switch and a starter switch, means for opening and closing said switches, and means operative for preventing the first mentioned means from closing the starter switch, said second mentioned means being rendered inoperative upon opening of the ignition switch.

11. A starting and ignition control for an engine having starting and ignition circuits, comprising means for opening and closing said circuits, means operative for holding the first mentioned means against closing the starting circuit, said second mentioned means being rendered inoperative upon opening of the ignition circuit.
